CLAIM

We claim the ornamental design for a control panel for a compressor, as shown and described.

DESCRIPTION

FIG. 1 is a perspective view of a compressor that includes a control panel that embodies the ornamental design of the present invention;

FIG. 2 is a perspective view of the control panel of FIG. 1; FIG. 3 is top view of the control panel of FIG. 1; and, FIG. 4 is front view of the control panel of FIG. 1.

The broken line showings in FIGS. 1-4 are for illustrative purposes only and form no part of the claimed design.
